UNITED STATES PATENT OFFICE.

PURDY NEWTON McGLOTHLEN, OF YAKIMA, WASHINGTON.

BOX-NAILING BENCH.

1,303,488.

Specification of Letters Patent. Patented May 13, 1919.

Application filed August 31, 1918. Serial No. 252,188.

To all whom it may concern:

Be it known that I, PURDY NEWTON McGLOTHLEN, a citizen of the United States, residing at Yakima, in the county of Yakima 5 and State of Washington, have invented certain new and useful Improvements in Box-Nailing Benches, of which the following is a specification, reference being had to the accompanying drawings.

10 This invention relates to box forming machines, and particularly to a machine for holding the ends of box blanks in position while the side walls of the box are being nailed in place.

15 One object of the invention is to provide a blank supporting table with end blank clamps adapted to resiliently clamp upon the box ends and support them while the sides of the box are being nailed in place.

20 A further object of the invention is to provide a machine of this character with a table having folding legs and folding braces, and in this connection to provide a nail stripper support which is foldable in upon 25 the table and a cleat pan support which is also foldable into or out of operative position.

Still another object is to provide a table 30 of this character which may be readily adapted for use either as a left hand or a right hand bench, or table, so as to fit the table or bench for use by either a right or a left handed man.

Another object is to provide a construction 35 of this kind in which the box clamps on one side are adjustable toward or from the box clamps on the opposite side, to thereby adjust the machine for operation of boxes of different lengths.

40 Still another object is to provide an attachment whereby relatively shallow boxes may be assembled.

Other objects will appear in the course of the following description.

45 My invention is illustrated in the accompanying drawings, wherein:

Figure 1 is a top plan view of a bench constructed in accordance with my invention;

50 Fig. 2 is a front elevation of the construction illustrated in Fig. 1;

Fig. 3 is a longitudinal vertical sectional view;

55 Fig. 4 is a fragmentary horizontal sectional view on an enlarged scale on the line 4-4 of Fig. 2;

Fig. 5 is a like view to Fig. 4 but on the line 5-5 of Fig. 2;

Fig. 6 is a fragmentary sectional view on the line 6-6 of Fig. 1;

Fig. 7 is a fragmentary top plan view of the forward end of the bench showing my supporting attachment applied thereon;

Fig. 8 is a fragmentary vertical longitudinal section of the bench showing the attachment thereon; and

Fig. 9 is a perspective view of one of the filler blocks used between the clamp wings.

Referring to Figs. 1, 2 and 3, it will be seen that my improved bench comprises the longitudinal planks 10, which may be of any suitable length and which are supported in spaced relation to each other by transverse forward and end braces or cross pieces 11 disposed beneath the longitudinal members 10 and nailed or otherwise rigidly attached thereto.

The table thus formed is supported by four legs. There are a pair of forward legs 12 and rear legs 13, disposed inward of the cross pieces 11 and hinged by hinges 14 to the members 10 so that the legs 12 and 13 will fold up in parallel relation to the members 10.

These legs are disposed in offset relation to each other, as illustrated in Fig. 2, 85 so that the legs may be folded. The legs are held in their normal or supporting position by means of a pair of forwardly and rearwardly extending braces 15, each brace being pivoted at 16 to the corresponding rear leg 90

and being connected to the corresponding forward leg by means of a removable bolt or screw 17. The supporting frame is further braced by means of a medially disposed brace 18, hinged at 19 to the forward transverse member 11 and notched at its rear end to engage over a transversely extending brace 20 attached to the rear legs 13.

It will be seen that the braces 15 can fold back into a position parallel to the legs 13 when the legs 100 are folded and that the brace 18 can also fold parallel to the members 10, thus providing for a very compact table when folded and for easy transportation.

Mounted upon the table formed by the 105 members 10 and extending from the front to the rear thereof are the vertically disposed supporting members or boards 21 and 21^a, one on each of the members 10. The member 21^a is shown as rigidly held in position 110 against any lateral movement or adjustment, by means of the angle irons 22, as illustrated

in Fig. 6. The member 21 is intended to be adjusted toward or from the member 21^a and to this end is partially supported by means of an angle iron 23 which is slotted on its base and held to the table by means of a wing bolt 24 passing through the slot. These members 21 and 21^a are connected to each other by means of forward and rearward transversely extending tie rods 25, each tie rod being made in two sections connected by a turn buckle 26. By rotating these turn buckles, the member 21 may be drawn toward or forced away from the member 21^a within certain limits and then the member 21 is braced in its adjusted position by tightening the bolt 24.

The members 21 and 21^a do not extend the full length of the table, but terminate short of the forward end thereof and disposed on each side of the members 21 and 21^a are the clamping wings 27 and 28, there being a pair of these clamping wings for each member 21 or 21^a and the wing 27 extending beyond the wing 28. These wings 27 and 28 extend toward the forward edge of the table and are adapted to receive between them the end boards of the box. Attached to the table, immediately beneath the space between each pair of wings, is a strip of metal 29 upon which the end board of the box is adapted to rest when nailing is being done.

The member 27 on one side of the table has uprights 30 extending up from it forming guides whereby the position of the slats on the completed box may be indicated. The members 27 and 28 are yieldingly held to the member 21 or 21^a, as illustrated in detail in Figs. 4 and 5. Fig. 4 illustrates the manner of engaging the wings 27 and 28 with the support 21 on the right hand side of the table while Fig. 5 shows the manner in which the wings 27 and 28 are engaged with the support 21^a upon the left hand side of the table. In Fig. 4 the rear ends of the wings 27 and 28 are engaged with the supporting member 21 by means of a bolt 35 which passes loosely through these wings 27 and 28 but the wing 28 is held in spaced relation to the support 21 by means of a spring 37 disposed partly in a recess 36 in the member 21. This spring urges the wing 27 against the member 21 but urges the member 28 in slightly spaced relation to the member 21, permitting, however, a slight movement of the members 27 and 28 toward or from each other. The wings 27 and 28 at their forward ends are urged against the member 21 by the bolts 31 and 34. The bolt 31 passes through the member 27, through the member 21 and through an enlarged opening in the wing 28. The spring 33 bears at one end against the wing nut 32 and at its other end bears against the member 21. Thus the wing 27 is yieldingly urged toward the member 21. The wing 28 is urged to-

ward the member 21 by a spring 33 surrounding a bolt 34 and bearing at one end against the nut 32 and at the other against the member 28.

On the left hand side of the machine, the wing 27 is rigidly engaged with the member 21^a so that it cannot yield, but the member 28 is urged toward the member 21^a by bolts 34 and 35 operating in the same manner as the bolts 34 and 35 in Fig. 4. The reason for holding the wing 27 rigid with the member 21^a is that it is from this side that the workman operates. In other words, in making the box one end of the box is first inserted against the member 21^a and the attached wing 27 and then the other end of the box inserted between the clamping wings 27 and 28 on the opposite side. Thus any slight differences in length in the box are provided for by permitting the end abutted against the member 21 to yield slightly in one direction or the other.

Mounted upon the members 10 is a shuck rack for supporting blanks, the rack as illustrated in Fig. 3 being composed of a pair of irons 39, each iron having a portion extending parallel to the table and being bent at its ends to form downwardly extending ends 40 which are detachably connected to the table by means of bolts and wing nuts 41. The irons 39 extend from a point rearward of the forward edges of the members 21 and 21^a to the rear edge of the table and to the portions 40 are attached the upright irons 42, these irons being detachably connected to the portions 40. The box blanks are adapted to be supported by these irons 39.

Attached to one side of the table by means of a bracket is a semi-cylindrical metallic cleat pan 43, the bracket being composed of two sections 44 and 45 engaged with the table by means of the thumb screws 46 and with the back wall of the cleat pan by means of a bolt 47 having a wing nut. On the opposite side of the table is disposed the nail strip rack, designated generally 48, formed of two brackets 49 and connecting cross pieces and adapted to support a box 50. The cleat pan and its bracket and the rack 48 may be transposed in position so that the bench may be arranged either for a right handed or a left handed man. As illustrated the bench is arranged for a right handed man.

In the operation of this work holder, as far as illustrated, the sides of the box and the bottoms of the box are placed upon the rack formed by the irons 39. The ends of the boxes are placed on the floor handy to the operator. The operator picks up the ends of the boxes two at a time and these ends are placed in the wings first. Then the operator reaches forward and takes the side from the shuck rack and places it onto the

side edges of the box, nails it on, and then the box is given a quarter turn and the two pieces of the bottoms are disposed on the bottom side of the box; then cleats are placed on the ends of the box and the bottoms and cleats nailed on. Then the box is given another quarter turn and the other side is nailed on. Uprights 57, illustrated in Figs. 1 and 2, may be disposed between the wings 28 to form vertically extending stops against which the sides may be abutted when nailing the sides on. The irons 42 are detachable from their upright position and may be laid down upon the irons 39 and bolted thereto so that they will lie down on top of the shuck rack. The container 43 is designed for the cleats and is semi-circular in form so that the cleats will not form a solid mass, but the cleats will be separated from each other.

The mechanism, as heretofore described, is adapted for the formation of relatively deep boxes but in order to form relatively shallow boxes, such as are used for prunes, I provide an attachment which is illustrated in Figs. 7 to 9. This attachment comprises a pair of angular brackets, designated 51, the ends of which are detachably connected to a corresponding forward leg 12 by means of bolts and wing nuts 52 and the horizontal portions of these brackets supporting the transverse nailing strip 53 which is approximately four inches wide and is disposed just in advance of the transverse braces 11. The distance from the top of the wings 27 and 28 to the metallic strips 29 is too deep to support shallow box ends and for that reason I provide a filler 54 for each pair of wing clamps, which is adapted to be inserted between said wing clamps and which is provided upon its upper face with a metal strip 55 corresponding to the metal strip 29. The forward end of this filler 54 is also provided with a metallic strip 56 which is attached to the end of the corresponding member 10 by means of a screw or other attaching device. By this means the relatively narrow end blank may be inserted between the wings 27 and 28 and rest upon the metallic strip 55, while one side of the box is being nailed to the end blank. When this has been accomplished, the partially completed box is disposed upon the cross bar 53 with the bottom in a vertical position and then one side of the box is nailed in place and the box turned half over and the other side is nailed in place.

It will be seen that this box holder is of very simple construction and that it is particularly convenient. The end blanks may be easily inserted within the clamps by disposing the end blank with its end against the member 28 and then forcing the blank laterally outward to engage with the member 27 and force the member 27 laterally

outward until the blank will slip in between the members 27 and 28. The springs will then hold the end blanks very rigidly in position while the nailing is being effected.

The device may be readily taken apart and folded for transportation. All of the parts which go to make up the box are supported within convenient reaching distance of the operator.

I claim:

1. A work support of the character described comprising a table, oppositely disposed pairs of vertical work engaging clamping wings mounted upon the table and adapted to receive the end blanks of a box between the wings, pairs of clamping wings being relatively adjustable toward or from each other, one wing of one pair of clamping wings being rigidly mounted upon the table, and vertically disposed guide members carried by said rigid clamping wing extending upward therefrom to indicate the position of slats to be nailed to said end blanks.

2. A work supporting bench of the character described comprising a table, a pair of vertical forwardly and rearwardly extending members mounted upon the table and spaced from the forward edge thereof, a pair of clamping wings yieldingly mounted upon each of the vertical members and extending to the forward edge of the table and resiliently urged toward each other, one of said vertical members being adjustable toward or from the other vertical member.

3. A work supporting bench including a table, forwardly and rearwardly extending vertical members mounted upon the table, the forward edges of said members being spaced from the forward edge of the table, tie rods connecting said members, the tie rods being adapted to be shortened or lengthened whereby to adjust the members, means holding said members to the table, and two pairs of clamping wings, one pair for each vertical member disposed on each side thereof and extending to the forward edge of the table, means loosely connecting the rear ends of said clamping wings to the corresponding vertical member, and means yieldingly urging the wings toward each other.

4. A work supporting bench of the character described comprising a table, vertically disposed, forwardly and rearwardly extending members mounted upon the table, one of said members being rigidly connected to the table and the other adjustable toward or from the rigid member, the forward edges of said vertical members being spaced from the forward edge of the table, two pairs of clamping wings, one pair for each vertical member disposed on each side thereof and extending toward the forward edge of the table, means yieldingly urging

the clamping wings of each pair toward the intervening vertical member, the clamping wings being less in height than the vertical member, and vertical stops disposed between the pairs of clamping members and with their edges in alignment with the forward edges of the vertical members.

5. The combination with a table having two pairs of forwardly extended blank clamps mounted thereon and resiliently urged toward each other, of fillers adapted to be inserted between the clamps and having a depth less than the depth of the clamps, means for detachably connecting the fillers in place and holding them in position, brackets operatively supported upon the table and extending beyond the front edge thereof, and a cross bar mounted upon said brackets.
10. A work supporting bench including a table, forwardly and rearwardly extending vertical members mounted upon the table, the forward edges of said members being

spaced from the forward edge of the table, means for holding said members upon the table but permitting the relative adjustment of the members toward or from each other, two pairs of clamping wings, one pair for each vertical member disposed on each side thereof and extending beyond the vertical member toward the forward edge of the table, said clamping wings being less in height than the corresponding vertical member, means yieldingly holding the clamping wings of each pair from relative outward movement, and a pair of supporting members disposed between the vertical members and extending upward from the table, then rearward and downward to provide a supporting rack.

15. In testimony whereof I hereunto affix my signature in the presence of two witnesses.

PURDY NEWTON McGLOTHLEN,
